JOHN W. KING, OF NEW YORK, N. Y.

Letters Patent No. 94,006, dated August 24, 1869.

IMPROVED CURTAIN-FIXTURE.

The Schedule referred to in these Letters Patent and making part of the same.

To all whom it may concern:

Be it known that I, JOHN W. KING, of the city, county, and State of New York, have invented a new and useful Improvement in Curtain-Fixtures; and I do hereby declare that the following is a full, clear, and exact description thereof, which will enable others skilled in the art to make and use the same, reference being had to the accompanying drawings, forming part of this specification.

This invention relates to that portion of a window-curtain fixture, which is called the roller, to which the curtain is attached, and from which it is suspended; and consists in the method of connecting the pivots or metallic bearings, and upper cord-pulley with the roller, and in the arrangement of the pulley outside of the bearing, as will be hereinafter more fully described.

In the accompanying sheet of drawings—

Figure 1 represents a longitudinal view of the roller, with the pivot and journal and pulley, attached and arranged according to my invention.

Figure 2 is a cross-section of fig. 1, through the line $x-x$.

Similar letters of reference indicate corresponding parts.

A, is the upper or curtain-roller.

This roller is usually revolved on pivots which are fast on metallic disks, which disks are fastened to the ends of the roller by tack-nails or by wood screws, driven through such disks into the end of the roller. This is the arrangement at both ends of the roller. At one end the cord-pulley forms the disk, the pivot being outside.

This method of fastening the pulley and pivots to the roller is extremely objectionable, as there is a constant tendency of the tacks or screws to work out of the end of the wood, thereby loosening the disks and preventing the proper working of the roller.

Another difficulty inseparable from this arrangement is, if the ends (or either of the ends) are not out perfectly square, or at right angles with the rod, the pivots are thrown out of true, and the tendency to general disorder in the fixture is constant and imminent.

B is the cord-pulley.

By making a journal or bearing for the rod between the pulley and the end of the roller, as seen in the drawing, the cord will not catch between the pulley and the pivot-bearing should it ever get off the pulley, thus another serious objection to the common fixture is obviated.

To make the fastening of the pivot and journal and pulley to the ends of the rod perfectly secure and durable, I form one or more ears, B B, on the disks C C, which ears I fasten to the roller by nails or screws, as seen in the drawing. This prevents any loosening of the disks, and it is immaterial whether the ends of the roller are square or not, the pivots or pivot and journal will always remain true with the roller.

In this example of my invention—

D is the pivot and E is the journal.

F is the cord-pulley.

By this arrangement, the cord is readily removed from the pulley, and should it, by any means, run off the pulley, it cannot catch and become wedged or tangled, as it frequently does.

The ordinary curtain-fixture (especially this portion) is so defective that it is really one of the standing annoyances of the household.

By my arrangement, all objections are obviated. The fixture will operate from year to year with perfect ease and certainty.

Having thus described my invention,

I claim as new, and desire to secure by Letters Patent—

1. The combination, with a cord-pulley and disk, of the journal E and ears B, all fitted together, as and for the purpose specified.

2. The subject-matter of above clause, in combination with the roller A, the ears B, disk C, and pivot D, arranged on the other end of the roller, as shown and described.

The above specification of my invention signed by me, this 22d day of June, 1869.

JOHN W. KING.
